ELECTRIC FURNACE

Original Filed Sept. 7, 1916

Inventor

William E. Moore,

By *John H. Koch*
his Attorney

UNITED STATES PATENT OFFICE.

WILLIAM E. MOORE, OF PITTSBURGH, PENNSYLVANIA.

ELECTRIC FURNACE.

Application filed September 7, 1916, Serial No. 118,890. Renewed October 3, 1928.

This invention relates more especially to improvements in arc type electric steel melting and refining furnaces.

In this class of furnace it has heretofore been customary to melt down the cold scrap with the same voltage which is used for refining, and on the refining operation to reduce the current, that is, the power in the furnace to keep the temperature within the limits which the refractory linings and roof of the furnace will stand without too much deterioration.

I find that when melting steel, it is possible to run with much higher energy input and longer arcs without damage to the refractories so long as there is unmelted steel in the furnace which keeps the temperature constant, but when refining it is best to materially reduce the power and shorten the arcs to keep within safe temperature limits on the refractories. It is, however, desirable to run at much higher power for melting than for refining in order to reduce the heat losses from radiation per ton melted and obtain a greater output per day from a given size furnace.

I have also found it extremely important when refining to run with a very short arc, say 50 volts, to prevent radiation at arc temperature from injuring the furnace walls, whereas, when melting a much longer arc is permissible and also desirable to prevent the fragments of scrap caving in to the cavities moltened by the arcs and contacting with the electrodes thus causing short circuits; and also to get increased power into the furnace without increasing the already enormously large currents, or requiring conductors and electrodes of unwieldy size in cross section.

I have found too, that in an arc playing from a carbon or graphite electrode to scrap metal or to a slag containing lime, silica, etc., there is a rectifying effect on the alternating currents tending to permit heavier current to flow in one direction for one-half wave length than in the other, and that if this rectified current be caused to flow down through the metal bath and furnace bottom, it tends to agitate the metal and prevent hot spots or a cold bottom by circulating the bath and brings it into more rapid circulation with the overlying highly heated slags which are depended upon in a large measure to refine steel.

The primary object of this invention may

be stated generally to expedite or shorten the time involved in melting and refining steel, allowing the use of smaller conductors and electrodes and more thorough heating and mixing the bath, in this type of furnace, and this I accomplish first by providing means for obtaining a large variation of the power input in the furnace by varying the arc voltage without materially varying the current through the arcs, thus permitting rapid melting with electrodes and secondary leads of minimum size. Second, by effecting an electrical connection between the conducting bottom of the furnace and a neutral point in the secondary windings of the transformers so as to permit a heavy flow of rectified or direct current for better heating and mixing the bottom of the bath, and third, by including in the secondary circuit of the transformer a reversing switch by which still greater current flow may be effected through the bath in refining.

In order to more particularly describe my invention, reference will be had to the accompanying drawings in which,

Fig. 1, is a diagrammatic view illustrating one form of my invention;

Fig. 2, a diagram showing the star or Y connection of the transformer primaries when refining, and

Fig. 3, a diagram showing delta connections of the transformer primaries when melting.

In the accompanying drawings, the furnace proper illustrated is of the three phase arc type in which 1, 2 and 3 represent the three arcing electrodes. These electrodes extend through the furnace top 4 and may be supported in the usual or any desired way. They are usually mounted upon mechanism for adjusting them vertically. The arched top 4 of the furnace is supported upon side walls 5, composed of so-called "acid" brick down to a point several inches above the slag level, and preferably of so-called "basic" brick below this point. The bottom lining of the furnace is formed preferably in two or more layers 6 and 7, the former composed of magnesite, dolomite, or other refractory material, and the latter of a mixture of refractory material and such better conducting material as carbon, graphite or metal turnings or similar conducting material progressively increasing in conductivity towards the bottom and rammed or sintered in. I do not, however, limit my invention to this

particular way of making the furnace bottom conducting. The sides and bottom of the furnace are enclosed in a metal shell 8. In this drawing, 9 represents the metal bath, 5 and 10 the slag.

Current is supplied to the furnace from three transformers 11, 12 and 13, in which the secondaries connected to the electrodes are Y connected. Tapped on to the neutral point in this Y connection is a conductor 14 electrically connected to the furnace shell 8.

Connected in the secondary circuit of transformer 12 is a reversing switch 15, the function of which will later be described.

The primaries of the three transformers are connected to the power mains 16, 17 and 18 through two switches 19 and 20, the former of which when closed connects the primaries in Y or star formation, and the latter when closed connects them in delta formation. These two switches may be inter-connected by a rod 21 or other suitable means whereby when one is closed, the other

25 is always open. When melting, switch 20 is closed and switch 19 open. This connects the primaries of the transformers in delta formation. In refining, switch 19 is closed, and switch 20 30 open, thus connecting the primaries in Y or star formation. By means of this arrangement a large variation of the power 35 input to the furnace may be secured by varying the current through the arcs, thus permitting more rapid melting with given size electrodes and secondary leads.

By connecting the neutral point of the secondaries of the transformers to the metal shell of the furnace 8, a direct current flow, 40 due to the rectifying effect hereinbefore referred to, is effected from the electrodes through the metal bath, which causes a bottom heating and agitation of the bath, as above pointed out.

When the upper layers of the lining of the bottom of this furnace become highly heated, they become electrically conducting and therefore form a path for current from the metal bath to the top layer which is rendered electrically conducting by the heat of the furnace, thence to the lower layers of the bottom which are made conducting at lower temperatures by reason of their being 55 intermixed with conducting materials such as carbon, graphite or other material in the manner above described, thence to metal shell 8.

If switch 15 be thrown in such direction 60 as to reverse the normal flow of current from the secondary of one transformer 12, through the electrode 2, a portion of the alternating as well as the rectified current is caused to flow through the bottom in the 65 manner stated, and this further expedites

the refining process by heating and mixing the bottom of the bath.

Without limiting my invention to the specific form herein shown, what I claim is:

1. An electric furnace having three arcing electrodes, and a refractory bottom rendered electrically conducting, transformer secondaries connected to said electrodes, an electrical connection from a neutral point in said secondaries to said conducting bottom, and switching means in the transformer primaries for varying the arc voltage between the melting and refining operations. 70

2. An electric furnace having three arcing electrodes, and a refractory bottom rendered

electrically conducting, transformer secondaries connected to said electrodes in Y formation, a conductor leading from a neutral point in the secondary connections to said

conducting bottom, and switching means in

the transformer primaries for varying the

arc voltage between the melting and refining operations. 80

3. An electric furnace having three arcing electrodes, and a refractory bottom rendered

electrically conducting, an electrically con-

ducting shell, transformers for supplying

electric power to said electrodes and having

secondaries connected to said electrodes, an

electrical connection from a neutral point or

neutral points in said secondary connections

to the conducting shell of said furnace, and

switching means for connecting the pri-

maries of said transformers for varying the

arc voltage between the melting and refining

operations. 90

4. An electric furnace having arcing elec-

trodes, and a refractory bottom rendered

electrically conducting, transformers for

supplying electric power to said electrodes

and having secondaries connected to said

electrodes in poly-phase formation, an elec-

trical connection from equipotential points

in said secondary connection to the conduct-

ing bottom of said furnace, and switching

means for connecting the primaries of said

transformer in high voltage formation or

in low voltage formation at will. 100

5. In the manufacture of steel and other

metals in an electric furnace having three

electrodes connected in a three phase circuit,

and a bottom capable of conducting electric-

ity, the method which consists in causing

current to pass from said electrodes through

the charge and the material of the furnace

bottom to a neutral point in the three phase

circuit. 110

6. An electric furnace having three arcing

electrodes connected in a three phase circuit,

and a bottom susceptible of conducting elec-

tricity only when hot, and conducting means

forming a path for electric current from the

furnace charge and through the material of

the furnace bottom, around the electrodes,

to a neutral point in the three phase system. 120

130

7. The combination with an electric furnace for melting and refining iron and steel, such furnace having a refractory lining and three arcing electrodes, of a three phase 5 transformer having a set of primary windings adapted to be connected to a source of current supply, and a set of secondary windings, a conductor extending from each of said secondary windings to one of said electrodes, switching means for changing the connections of one only of said sets of windings from star to delta, or vice versa, without altering the connections of the other set whereby the voltage at the arcs may be varied, and means providing a path through the furnace bottom for current flow between the molten charge and neutral point of the secondary windings.

8. An electric furnace having three arcing 20 electrodes and a bottom susceptible of conducting electricity, a transformer comprising three-phase primary and secondary windings, said secondary windings being connected in star formation, connections between the terminals of said secondary windings and said arcing electrodes, a connec- 25 tions

tion between the neutral point of said secondary windings and the bottom of said furnace, means for connecting said primary windings with a three-phase source of supply, and means for reversing the normal relative direction of current flow through one of said electrodes, whereby a current is caused to flow through said furnace bottom.

9. An electric furnace having three arcing electrodes and a bottom susceptible of conducting electricity, a transformer comprising three-phase primary and secondary sets of windings, said secondary windings being connected in star formation, connections between the terminals of said secondary windings and said arcing electrodes, a connection between the neutral point of said secondary windings and the bottom of said furnace, means for connecting said primary windings 35 with a three-phase source of supply, and means for reversing the connections of one-phase of one of said sets of windings, whereby a current is caused to flow through said furnace bottom.

In testimony whereof I affix my signature.
WILLIAM E. MOORE.
